DESIGN FOR A GAME BOARD

Evan T. Tishock, Cleveland, Ohio

Application June 21, 1941, Serial No. 101,603

Term of patent 14 years

To all whom it may concern:

Be it known that I, Evan T. Tishock, a citizen of the United States, residing at Cleveland, in the county of Cuyahoga and State of Ohio, have invented a new, original, and ornamental Design for a Game Board, of which the following is a specification, reference being had to the accompanying drawing, forming a part thereof,

I claim:

The ornamental design for a game board, as shown.

EVAN T. TISHOCK.
